REINFORCING WAIST BAND STRUCTURE

Filed June 20, 1961

illustrated in FIG. 6. The band 20 is folded twice to form creases 23 and 24 therein and arranged so that the lateral edge 21 lies adjacent the crease 24 and in the same plane therewith. The band 20 is guided along the surface of a table top 55a and between a pair of rollers 56a and 59a whereby the creases 23 and 24 are formed in the band. As may be seen in FIG. 2, roller 56a is positioned within an opening 58a in the table surface 55a and the roller 59a is disposed above the surface of the table 55a. After the creases 23 and 24 have been formed in the band, the band is passed between the table surface 55a and a heating element 62a whereby the thermo-setting material is heat-set, after which it is allowed to cool with the consequent formation of permanent creases 23 and 24 therein and a permanent tendency for the band to assume the folded arrangement shown in FIG. 2.

FIG. 3 illustrates one manner of forming the band 31 illustrated in FIG. 7 in which the band of thermo-setting material has been folded three times to form the three creases 37, 38 and 39 and arranged so that the creases 37 and 39 lie adjacent each other and in the same plane. The folded band of thermo-setting material is passed along a table top 55b between a lower roller 56b positioned in an opening 58b beneath a table top 55b and a contact roller 59b positioned above the surface of the table top. After formation of the creases 37, 38 and 39 by the rollers 56b and 59b, the material passes between the surface 55b of the table and a heating element 62b, whereby the band 31 is heat-set to form permanent creases 37, 38 and 39 and to establish the tendency of the band to assume the folded arrangement shown in FIG. 3.

FIG. 4 illustrates one manner of producing the reinforcing band 48 shown in FIG. 8 in which the aforesaid band is applied to an outwardly convex mold 55c and arranged to pass beneath an inwardly concave roller 59c and subsequently beneath a heat-setting element 62c by means of which the curve formed in the band 48 is permanently set thereby producing a band having a convex side and a concave side and one which a tendency is permanently established to assume the aforesaid shape.

FIG. 9 illustrates a typical waist band construction as provided in accordance with this invention in which the outer cloth 70 of a waist band having inwardly turned edges 71 and 72 is stitched to a garment 73 and to the inner cloth or lining 74 of the waist band, said inner cloth having inwardly turned ends 75 and 76. To the inside of the waist band adjacent the inner cloth or lining 74 thereof, is stitched the reinforcing waist band structure 10 so that the generally convex side comprising the surfaces 13 and 14 face against the inner cloth or lining 74 of the waist band and so that the concave side comprising surfaces 15 and 16 face away from the inner cloth or lining 74 toward the body of the wearer. The dot and dash lines of FIG. 10 show the position which the band 10 naturally tends to assume owing to the heat-setting process to which the aforesaid band has been subjected and illustrates the manner in which the band 10 tends to pull the waist band generally inward toward the body of the wearer.

FIG. 11 illustrates the application of the reinforcing band 20 to the waist band of FIG. 9 and the dot and dash lines thereof indicate the position which the reinforcing structure 20 tends normally to assume, thereby

tending to pull the waist band inwardly toward the body of the wearer.

FIG. 12 illustrates the application of the band 31 to the waist band of FIG. 9 and the dot and dash lines thereof indicate the position which the band 31 tends normally to assume, thereby pulling the waist band generally inward toward the body of the wearer.

And finally, FIG. 13 illustrates the application of the band 48 to the waist band of FIG. 9, the dot and dash lines thereof indicating the position which the band 48 tends normally to assume, similarly pulling the waist band generally inwardly toward the body of the wearer.

In each of the aforescribed modifications of the invention, the reinforcing waist band structure is stitched to the inward side of the waist band so that the side of the structure which would normally be generally concave faces the body of the wearer.

It will be apparent that it is an important advantage of the waist band construction as provided in accordance with this invention that the waist bands of garments so constructed have a generally normal tendency to turn inwardly toward the body of the wearer and not to become distorted and to flare outwardly of the body of the wearer as is normally the case.

It will be apparent too that it is an important advantage of the reinforcing waist band structure as provided in accordance with the invention, that by means of the heat-set thermo-setting reinforcing material, the waist bands of garments are thereby permanently provided with an inwardly turning tendency which endures for the life of the garment.

Although this invention has been described with reference to specific forms and embodiments thereof, it will be evident that a great number of variations may be made without departing from the spirit and the scope of this invention. For example, parts may be reversed, equivalent elements may be substituted for those specifically disclosed, and certain features of the invention may be used independently of other features, all without departing from the spirit and scope of this invention as defined in the appended claim.

Having thus described my invention, I claim:

In a waist band construction including an outer fabric and an inner fabric secured to one another, a reinforcing waist band structure comprising an elongated flexible band of thermosetting material secured to the inward side of said inner fabric at opposite lateral edges thereof, said band of thermosetting material having a relaxed permanently set generally concave configuration and said concave surface facing inwardly of said garment, whereby upon being distorted from said concave configuration said band of thermosetting material tends to turn said opposite lateral edges of said inner fabric inwardly.
